VISIBLE INDEX CARD HOLDER

Max Vogel, Bridgeport, Conn.

Application December 5, 1938, Serial No. 243,918

11 Claims. (Cl. 129—16.7)

The present invention relates to an improvement in visible index card holder, particularly of the type which is adapted to be secured to the upper edge of an index card to retain it in a supporting frame in sierate arrangement, with a number of such cards in successive overlapping relation. It is an object of the invention to provide a holder which may be engaged with the edge of the card by sliding the card longitudinally along the holder, and thereupon will securely retain the card against both longitudinal and transverse movement, at the same time providing a protective covering for the edge of the card. It is particularly proposed to provide a holder formed from sheet metal, and, to the end of providing a relatively inexpensive structure which may be produced by efficient manufacturing methods, it is proposed to form the holder from a single piece of sheet metal having its various co-operative parts formed by bending portions of the metal in relation to other portions along parallel bending lines. Another object is to provide a card having an edge structure adapted to facilitate its engagement with the holder as well as to facilitate its removal.

With the above and other objects in view, an embodiment of the invention is shown in the accompanying drawing, and this embodiment will be hereinafter more fully described with reference thereto, and the invention will be finally pointed out in the claims.

In the drawing:

Fig. 1 is a perspective view of a card holder, according to the exemplary illustrated embodiment of the invention, the intermediate portion being broken away and showing the cross-sectional shape.

Fig. 2 is a perspective view of the upper end of the card adapted to be inserted in the holder, the intermediate portion being broken away and showing the cross-sectional shape.

Fig. 3 is a perspective view showing the card engaged in the holder, the intermediate portion being broken away and showing the cross-sectional shape.

Fig. 4 is an enlarged front elevation of the left hand end portion of the holder, it being understood that the right hand end portion is of identical but reversed construction.

Fig. 5 is a top edge view thereof.

Fig. 6 is a sectional view taken along the line 6—6 of Fig. 4.

Fig. 7 is a sectional view taken along the line 55 7—7 of Fig. 4.

Fig. 8 is a view similar to Fig. 4 and showing the card engaged in the holder.

Fig. 9 is a top edge view thereof.

Fig. 10 is a sectional view taken along the line 10—10 of Fig. 8.

Fig. 11 is a top edge view of the left hand end of the holder and showing the right hand edge of the card being engaged therewith.

Fig. 12 is a top view showing the manner in which the card is slightly bent at its end to disengage it from the holder, the left hand edge of the card being shown just prior to its being withdrawn from the holder.

Fig. 13 is a perspective view showing the frame containing a series of holders and cards.

Fig. 14 is a perspective view of a retaining follower member employed in cooperation with the frame.

Similar reference characters indicate corresponding parts throughout the several figures of the drawing.

Referring to the drawing the holder, which is bent from sheet metal, comprises a back or base portion 10 of elongated rectangular form having a flange 11 extending the full length of its lower edge and bent upwardly into contacting relation with its front surface, the upper edge of this flange being spaced downwardly from the upper edge of the base and adapted to constitute a card retaining abutment 11a, as will hereinafter more fully appear.

At each end of the holder there is provided at the upper edge of the base a flange portion 12, corresponding substantially in width to the width of the base and bent downwardly over the forward surfaces of the base 10 and the flange 11 in contacting relation with the flange 11 and constituting an end abutment 12a for the card, as will presently more fully appear. Along the upper edge of the base 10 between the end flanges 12 there is provided a flange 13, the ends of which are spaced from the inner abutment edges 12a of the flanges 12, this flange 13 being bent downwardly at the forward side of the base 10 in parallel spaced relation to the forward surfaces of the base 10 and the flange 11, the spacing between the flange 13 and the flange 11 being substantially the width of a card thickness, while the space between the flange 13 and the forward surface of the base 10 is substantially equal to double card thickness.

The card 14 is provided at its upper edge with a fold flange 15, preferably produced by a score line, and bent downwardly upon the rearward face and which is of a width substantially corre-

sponding to the transverse width of the space between the upper abutment edge 11^a of the flange 11 and the inner surface of the fold of the flange 13, so that such flange 15 is adapted for sliding engagement in said space. The ends of the flange 15 are cut at an angle, as at 16, which is adapted to facilitate the insertion and removal of the card, as will presently more fully appear. The card is preferably provided with a score line 17, which in the engaged relation with the holder is slightly below the lower edge of the holder, and provides a hinge line for the purpose of swinging the card from flat closed position to an upright open position.

15 As shown in Fig. 11 the card is inserted in the holder by first engaging the end of the upper edge in the space beneath the flange 13 and above the abutment flange 11, the inclined end 16 of the card flange 15 facilitating the insertion by eliminating square corners at the ends of the flange which might catch upon the edges of the holder and guiding the lower edge of the flange 15 into parallel engagement with the upper abutment edge 11^a of the flange 11, even 20 though the card may not be parallel as it is inserted. The inclined ends 16 also render the ends of the upper margin more flexible, which facilitates insertion. The card is then drawn longitudinally along the holder until its end edges 25 engage in abutting relation within the inner abutment edges 12^a of the end flanges 12, the longitudinal dimension of the card being designed so that it fits the holder in this manner. The inserted card is therefore firmly retained against 30 both longitudinal and transverse movement. In order to disengage the card one end portion is bent slightly outwardly as shown in Fig. 12, so as to disengage the end edge of the card from the inner abutment edge 12^a of the flange 12, whereupon the card may be withdrawn from the 35 holder, the inclined cuts 16 preventing any possibility of the flange ends catching upon the abutment edges 12^a.

I have shown in Fig. 13 a series of card holders, 40 certain of which have cards attached, and arranged in a frame member 18 of rectangular form having flanges 19 at each of its longitudinal edges bent inwardly in spaced relation to the base, the width of these flanges being slightly less than the longitudinal dimension of the flanges 12, so that the flanges 12 may be engaged beneath the flanges 19 to be retained thereby, while the end edges of the cards are inwardly spaced from the edges of the flanges 19. The cards may therefore 45 be conveniently inserted and removed, if desired, without removing the holders from the frame.

At the upper end of the frame there is provided a metal cover member 20 hinged, as at 21, and 50 which will close down upon the upper card in the frame, being of sufficient weight to retain such card in substantially flat closed position, the retaining of this upper card also retaining the remaining cards which are beneath it, each card 55 being offset with respect to the next card a distance corresponding to the width of the holder.

A retaining follower plate 22 is provided for retaining of the holders and cards in the upper portion of the frame, this plate being of a width 60 slightly greater than the width of the cards, so that its lower edge will be exposed below the lowermost card in the frame. The follower plate is provided with spring finger portions 23 at its side marginal portions which engage beneath the flanges 19 to thus frictionally retain the follower 65

in any position to which it is moved. The lower edge of the follower is provided with an upwardly bent finger engaging flange 24.

The holders, either with or without the cards attached, may be inserted in the frame from the 5 end, or they may be engaged at an intermediate point by placing one of the end portions 12 beneath one flange 19 with the holder in a diagonal position and then swinging the other end flange 12 beneath the other flange 19. They may be 10 similarly disengaged.

I have illustrated and described a preferred and satisfactory embodiment of the invention, but it will be understood that changes may be made therein, within the spirit and scope there- 15 of, as defined in the appended claims.

Having thus described my invention what I claim and desire to secure by Letters Patent is:

1. A visible card index holder, comprising an elongated strip member, transverse abutment means contiguous to each end of said strip member, longitudinal abutment means extending between said transverse abutment means in spaced parallel relation to the upper edge of said strip member, and pocket forming means comprising a portion extending forwardly from the upper edge of said strip member to provide a top wall in opposed transversely spaced relation to said longitudinal abutment means, and a downwardly extending wall portion disposed in forwardly 30 spaced relation to said strip member and extending below said longitudinal abutment means in forwardly spaced relation thereto, at least one end of said front wall portion terminating in longitudinally spaced relation to one of said trans- 35 verse abutment means.

2. A visible card index holder, comprising an elongated strip member, transverse abutment means contiguous to each end of said strip member, longitudinal abutment means extending between said transverse abutment means in spaced parallel relation to the upper edge of said strip member, and pocket forming means comprising a portion extending forwardly from the upper edge of said strip member to provide a top wall 45 in opposed transversely spaced relation to said longitudinal abutment means, and a downwardly extending wall portion disposed in forwardly 50 spaced relation to said strip member and extending below said longitudinal abutment means in forwardly spaced relation thereto, the ends of 55 said front wall portion terminating in longitudinally spaced relation to said transverse abutment means.

3. A visible card index holder, comprising an elongated strip member, transverse forwardly projecting abutment means contiguous at each end of said strip member, longitudinal forwardly projecting abutment means extending between said transverse abutment means in spaced parallel relation to the upper and lower edges of 60 said strip member, and pocket forming means comprising a flange portion parallel to and extending forwardly from the upper edge of said strip member to provide a top wall in opposed parallel transversely spaced relation to said longitudinal abutment means, and a downwardly extending wall portion disposed in forwardly spaced parallel relation to said strip member and extending below said longitudinal abutment means 65 in forwardly spaced relation thereto, at least one end of said front wall portion terminating in longitudinally spaced relation to one of said trans- 70 verse abutment means.

4. A visible card index holder, comprising an 75

elongated strip member, transverse abutment means longitudinally spaced from each end of said strip member, longitudinal abutment means extending between said transverse abutment means in spaced parallel relation to the upper edge of said strip member, and pocket forming means comprising a portion extending forwardly from the upper edge of said strip member to provide a top wall in opposed transversely spaced relation to said longitudinal abutment means, and a downwardly extending wall portion disposed in forwardly spaced relation to said strip member and extending below said longitudinal abutment means in forwardly spaced relation thereto, the ends of said front wall portion terminating in longitudinally spaced relation to said transverse abutment means.

5. A visible card index holder, comprising an elongated strip member, transverse abutment means contiguous to each end of said strip member, longitudinal abutment means extending between said transverse abutment means in spaced parallel relation to the upper edge of said strip member, and pocket forming means comprising a portion extending forwardly from the upper edge of said strip member to provide a top wall in opposed transversely spaced relation to said longitudinal abutment means, and a downwardly extending wall portion disposed in forwardly spaced relation to said strip member and extending below said longitudinal abutment means in forwardly spaced relation thereto, at least one end of said front wall portion terminating in longitudinally spaced relation to one of said transverse abutment means, and a card adapted to be inserted in said holder having a longitudinal abutment at its upper marginal portion adapted to be inserted longitudinally into the pocket between said strip member and wall portion through the space at the end of said wall portion.

6. A visible card index holder, comprising an elongated strip member, transverse abutment means contiguous to each end of said strip member, longitudinal abutment means extending between said transverse abutment means in spaced parallel relation to the upper edge of said strip member, and pocket forming means comprising a portion extending forwardly from the upper edge of said strip member to provide a top wall in opposed transversely spaced relation to said longitudinal abutment means, and a downwardly extending wall portion disposed in forwardly spaced relation to said strip member and extending below said longitudinal abutment means in forwardly spaced relation thereto, at least one end of said front wall portion terminating in longitudinally spaced relation to one of said transverse abutment means, and a card adapted to be inserted in said holder having a marginal flange folded down at its upper edge to provide a double thickness marginal portion, adapted to be inserted longitudinally into the pocket between said strip member and wall portion through the space at the end of said wall portion.

7. A visible card index holder, comprising an elongated strip member, transverse abutment means contiguous to each end of said strip member, longitudinal abutment means extending between said transverse abutment means in spaced parallel relation to the upper edge of said strip member, and pocket forming means comprising a portion extending forwardly from the upper edge of said strip member to provide a top wall in opposed transversely spaced relation to said longitudinal abutment means, and a downwardly ex-

tending wall portion disposed in forwardly spaced relation to said strip member and extending below said longitudinal abutment means in forwardly spaced relation thereto, at least one end of said front wall portion terminating in longitudinally spaced relation to one of said transverse abutment means, and a card adapted to be inserted in said holder having a marginal flange folded down at its upper edge to provide a double thickness marginal portion, adapted to be inserted longitudinally into the pocket between said strip member and wall portion through the space at the end of said wall portion, the edge of said flange at its ends being inclined.

8. A visible card index holder comprising an elongated strip including a base portion of elongated rectangular form, a longitudinally extending flange bent upwardly from the lower longitudinal edge of said base portion in overlying contacting relation to the front surface of said base portion, the upper edge of said flange being disposed in spaced and parallel relation to the upper edge of said base portion, flange portions at each end of said base portion bent downwardly from the upper edge thereof overlying and engaging the front surface of said upwardly bent flange, and a pocket forming flange extending forwardly from the upper edge of said base portion and downwardly in spaced parallel relation to the front surfaces of said base portion and said upwardly bent flange, the lower edge of said pocket forming flange being below the upper edge of said upwardly bent flange, and the end edges of said pocket forming flange being in inwardly spaced relation to the inner edges of said downwardly bent flanges.

9. A visible card index holder comprising an elongated strip including a base portion of elongated rectangular form, a longitudinally extending flange bent upwardly from the lower longitudinal edge of said base portion in overlying contacting relation to the front surface of said base portion, the upper edge of said flange being disposed in spaced and parallel relation to the upper edge of said base portion, flange portions at each end of said base portion bent downwardly from the upper edge thereof overlying and engaging the front surface of said upwardly bent flange, and a pocket forming flange extending forwardly from the upper edge of said base portion and downwardly in spaced parallel relation to the front surfaces of said base portion and said upwardly bent flange, the lower edge of said pocket forming flange being below the upper edge of said upwardly bent flange, and the end edges of said pocket forming flange being in inwardly spaced relation to the inner edges of said downwardly bent flanges, and a card adapted to be inserted in said holder having an upper marginal abutment portion of a width substantially corresponding to the width of the space between said pocket forming flange and the front surface of said base and adapted to be inserted longitudinally into said space through one of the spaces at the end edges of said pocket forming flange, said abutment portion of the card adapted to transversely abut the upper edge of said upwardly bent flange, and the ends of the card adapted to longitudinally abut the inner edges of said downwardly bent end flanges.

10. A visible card index holder, comprising an elongated strip member, transverse abutment means contiguous to an end of said strip member, longitudinal abutment means extending between the ends of said strip member in spaced

- parallel relation to the upper edge of said strip member, and pocket forming means comprising a portion extending forwardly from the upper edge of said strip member to provide a top wall 5
5 in opposed transversely spaced relation to said longitudinal abutment means, and a downwardly extending wall portion disposed in forwardly spaced relation to said strip member and extending below said longitudinal abutment means in 10
10 forwardly spaced relation thereto, at least one end of said front wall portion terminating in longitudinally spaced relation to said transverse abutment means.
11. A visible card index holder, comprising an 15
15 elongated strip member, transverse abutment means contiguous to an end of said strip mem-

ber, longitudinal abutment means extending between the ends of said strip member in spaced parallel relation to the upper edge of said strip member, and pocket forming means comprising a portion extending forwardly from the upper edge of said strip member to provide a top wall 5
5 in opposed transversely spaced relation to said longitudinal abutment means, and a downwardly extending wall portion disposed in forwardly spaced relation to said strip member and extending below said longitudinal abutment means in 10
10 forwardly spaced relation thereto, at least one end of said front wall portion terminating in longitudinally spaced relation to an end of said strip member.

MAX VOGEL.
